UNITED STATES PATENT OFFICE.

GLENWAY MAXON, JR., OF MILWAUKEE, WISCONSIN.

STRIKE-OFF FOR ROAD-FINISHING MACHINES.

1,386,348.

Specification of Letters Patent.

Patented Aug. 2, 1921.

Application filed August 21, 1920. Serial No. 405,082.

To all whom it may concern:

Be it known that I, GLENWAY MAXON, Jr., a citizen of the United States, and a resident of Milwaukee, in the county of Milwaukee and State of Wisconsin, have invented new and useful Improvements in Strike-Offs for Road-Finishing Machines, of which the following is a description, reference being had to the accompanying drawings, which are a part of this specification.

The invention relates to a strike off device for road-finishing machines.

In road-finishing machines the strike off functions to smooth off the uneven surface of the road, such as a concrete road, prior to the tamping operation and as the machine advances. Machines of this character are usually provided with wheels which run on rails or guides at the sides of the road. In such machines the forces imparted to the framework of the machine through a single reciprocating strike off sets up objectionable strains and stresses in the machine, and to obviate this difficulty I have provided a strike off device in which the strike off is composed of sections which move toward and away from each other and thereby counterbalance their reciprocal effect and thus relieve the frame and the rails of objectionable strains.

The invention further consists in the several features hereinafter set forth and more particularly defined by claims at the conclusion hereof.

35 In the drawings: Figure 1 is an end view of the device embodying the invention; Fig. 2 is a detail top view, parts being broken away and parts being shown in section; Fig. 3 is a section taken on the line 3-3 of Fig. 1.

In the drawings the numeral 4 designates generally the framework of the machine which is mounted on wheels 5 that run on rails or guides 6. The framework and wheels together with the driving mechanism (not particularly shown) are shown in my copending application, Serial No. 353,721, filed January 24, 1920, with which the strike off device involving this invention may be used, though it is to be understood that the strike off device hereinafter described may be used in connection with other road-finishing machines.

55 The strike off consists of two strike off members 7 and 8 which are suspended from the frame by means of rods 9 and chains 10

at their inner ends while their outer ends are free to slide over the top of the guides 6. These sections 7 and 8 are reciprocated toward each other and away from each other on the rotation of a drive shaft 11 by means of eccentrics 12 and 13 and connecting rods 14 and 15 which operatively connect the eccentrics 12 and 13 to bracket arms 16 and 17 on the respective strike off members 7 and 8. The eccentrics are arranged at 180 degrees with respect to each other so that as the shaft 11 rotates the members 7 and 8 move toward each other and then away from each other transversely of the road as the machine is moved forwardly. This, as previously pointed out, relieves the frame and the guide rails of objectionable strains. A plate 18 is secured to the member 7 and has a close sliding fit over the forward end of the member 8 so as to present a continuous surface against the concrete which is being acted upon by the strike off device.

20 The members 7 and 8 are each held in an upright position by means of U-shaped links 19 pivotally secured at their ends 20 to the back of the members 7 and 8 and pivotally secured intermediate their ends to eyed bolts 21 carried by the frame of the machine.

25 The strike off members 7 and 8 are raised and lowered by means of flexible connections 22 secured to the strike off members and running over small winding drums 23 upon a shaft 24 which is turned by a connection with a crank 25.

30 The members 7 and 8 are provided with metal edge strips or templets 26.

I desire it to be understood that this invention is not limited to any specific form or arrangement of parts except in so far as such limitations are specified in the claims.

35 What I claim as my invention is:

1. In a road finishing machine, a strike off device comprising a plurality of reciprocating strike off members, and means for moving said members transversely of the roadway toward and away from each other.

40 2. In a road-finishing machine, the combination with the frame, of a strike off device, comprising a pair of reciprocating strike off members disposed in the same plane, means for moving said members transversely of the roadway in opposite directions to each other, and an extension carried by one of said members slidable upon the other member.

45 3. In a road-finishing machine, the com-

bination with a frame, of a pair of strike off members suspended from the frame and positioned to extend transversely of the roadway, horizontally swinging links connecting said strike off members to the frame, and means for reciprocating said strike off members transversely of the road in opposite directions.

4. In a road-finishing machine, the combination with a wheeled frame, of a pair of strike off members suspended from the frame

and positioned transversely of the roadway in the same plane, an extension carried by one of the members slideable upon the other, a drive shaft, connections between said shaft and said members to move them in opposite directions, and horizontally swinging links connecting said strike off members to the frame. 15

In testimony whereof I affix my signature. 20

GLENWAY MAXON, JR.
